2025 RELEASE UNDER E.O. 14176

UNITED STATES PATENT OFFICE.

LEVIN D. VAUGHAN, OF PHILADELPHIA, PENNSYLVANIA.

TEMPERATURE-REGULATOR.

1,255,672.

Specification of Letters Patent. Patented Feb. 5, 1918.

Original application filed June 24, 1916, Serial No. 105,533. Divided and this application filed May 24, 1917. Serial No. 170,582.

To all whom it may concern:

Be it known that I, LEVIN D. VAUGHAN, a citizen of the United States, residing at Philadelphia, in the county of Philadelphia and State of Pennsylvania, have invented 5 certain new and useful Improvements in Temperature-Regulators, of which the following is a specification.

My invention relates to an improved 10 mechanism to be applied to boilers, hot water heaters and the like, for the purpose of automatically putting on, or shutting off, the draft at a predetermined time.

The objects of the invention are the provision of a temperature regulator operated 15 and controlled by means of a clock mechanism in combination with my expansion and contraction temperature regulating device, for which Letters Patent were issued to me 20 March 27th, 1917, No. 1,220,381, this present application being a division of the original application therefor, which is simple and durable in its construction and which will operate in a positive manner to control the 25 draft and regulate the fire and such other and further objects as may hereinafter appear.

For a full understanding of the invention and the merits thereof and also to acquire 30 a knowledge of the details of construction and the means for effecting the result, reference is to be had to the following description and accompanying drawings in which—

35 Figure 1 is a front view of a boiler with my temperature regulating device in place and my present device connected thereto;

Fig. 2 is a sectional view illustrating the 40 clock mechanism;

Fig. 3 is a detail view of the trigger or 45 trip mechanism in engagement and

Fig. 4 is a detail view of the trigger or trip mechanism out of engagement.

Similar reference characters refer to similar 50 parts throughout the drawings.

Referring to said drawings the numeral 10 represents a pipe connection to a boiler, or source of water supply, said pipe being threaded on its upper portion to receive a 55 Y shaped joint 11. One angle of said Y shaped joint 11, being a continuation of the water supply, by means of the pipes 15 and 16 carries the water to the radiators.

Secured to the upper part of the other 60 angle of said Y shaped joint 11 is a bushing or member 47 which acts as a support for

the saddle or yoke 46, said member 47 at its center of height being hexagonal. The yoke 46, projecting laterally upon opposite sides of the piston rod guide and having upwardly 60 extending arms 12 and 45, secured thereto by lock nuts as illustrated, is fastened to the bushing 47 also by means of lock nuts. The upwardly extending arm 12 is bifurcated at its upper end to receive loosely the lever 14, 65 which in this instance is a horizontally disposed beam, pivotally mounted, at an intermediate point, upon a pin 13^a. The upwardly extending arm 45 is slit to act as a guide for said lever 14 and to allow free play 70 thereof. Adjusting nuts 12^a are threaded on the upper end of the piston rod 13, as illustrated. The lever 14 has attached thereto in any suitable manner the weight 17. A flexible chain or cord 37 is secured to an 75 opening in the lever 14 and extends down and is fastened to a ring on the ash pit door 38 as illustrated. Also secured to an opening in said lever 14 are the connections 18 and 19 to the flue damper 20 as shown. 80

In my former application, on which Letters Patent were issued, as hereinbefore set forth, I have described in detail my method of regulating temperature by means of expansion and contraction in conjunction with 85 the mechanism just described. I now describe my clock mechanism in combination therewith to regulate the temperature by a time control.

A box or casing 31 is provided, one side 90 thereof, 30, being of glass in order that the operator may see the face of the clock 32. An alarm clock 32 of any suitable make is placed in the bottom of said box or casing 31 and is securely held in position there by 95 means of the strap 33 which is secured to the bottom of the casing by means of nuts 36. Said strap is adjusted by means of the buckle 33^a.

A chain or cord 21 secured to an opening in the lever 14 and passing over the guide pulleys 22 and 23 as illustrated and through an opening in the top of said casing 31, terminates in the ring 44. A bracket 29 is bolted to the inside wall of the casing 105 31 as illustrated and the trigger or trip member 42 is bolted thereon, by means of nut 43. A guide pulley 25 is secured to the under part of the upper portion of the casing 31 and a cord 26 passes over said pulley as shown, one end thereof being secured to an opening in a lever 27, said lever 110

27 being secured to the bracket 29 by the nut 28 as illustrated. The other end of said cord 26 is secured to a catch or hook member 34, which is hooked to the alarm winding key 35, on the back of the alarm clock 32.

16 The lever 27 is secured to bracket 29 by means of the nut 28 and is provided with a notch 48 at its free end to engage the trigger 49.

18 Briefly the operation of my clock mechanism is as follows:

15 The operator sets the alarm of the clock for a predetermined time. The member 34 is hooked to the alarm winding key 35, and the ring 44 on chain 26 is slipped over trigger 49, which is placed in engagement with the lever 27; this tightens up cord 26 and pulls up the weighted lever 14.

20 This action of the lever 14 closes the ash pit door 38 and the damper 20 in the flue.

25 When the predetermined time comes the alarm operates revolving the key winding member 35 which releases the hook 34. This action releases the trigger 49 from engagement with the lever 27, thereby freeing the cord 26 which allows lever 14 to return to its normal position. This action opening the ash pit door 38 and the damper 20 in 30 the flue.

I do not restrict myself to the exact de-

tails of construction, combination and arrangement herein set forth, it being obvious that minor variations thereof not involving the exercise of invention may be made by 35 the skilled mechanic, and such departure from what I have herein described and claimed not involving invention I consider as within the scope and terms of my claim.

Having thus described my invention what 40 is claimed as new and desired to be secured by Letters Patent is:

In a device of the character described, a clock provided with an alarm winding key and means connected thereto, comprising a 45 cord passing over a guide pulley, secured to an opening in the free end of a lever, a lever, means for engaging said lever with a trigger, the other end of said cord terminating in a catch member adapted to hook on 50 said winding key, whereby when said winding key revolves said catch member and said lever are released from engagement with said winding key and said trigger respectively, substantially as shown and described.

In testimony whereof I affix my signature in presence of two witnesses.

LEVIN D. VAUGHAN.
